F. W. PARSONS

PLATE VALVE UNLOADER

Filed Sept. 18, 1922

Inventor

Frederick W. Parsons

By His Attorney

Herbert Glazier

UNITED STATES PATENT OFFICE.

FREDERICK W. PARSONS, OF ELMIRA, NEW YORK, ASSIGNOR TO INGERSOLL-RAND COMPANY, OF JERSEY CITY, NEW JERSEY, A CORPORATION OF NEW JERSEY.

PLATE-VALVE UNLOADER.

Application filed September 18, 1922. Serial No. 588,918.

To all whom it may concern:

Be it known that I, FREDERICK W. PARSONS, a citizen of the United States, and a resident of Elmira, county of Chemung, 5 State of New York, have invented a certain Plate-Valve Unloader, of which the following is a specification, accompanied by drawings.

This invention relates to plate valves, but 10 more particularly to a plate valve unloader for compressors, by means of which a plate valve, preferably an inlet valve, is held open for unloading purposes.

The objects of the invention are to secure 15 a simple and efficient device, which will not readily get out of order, for holding a plate valve away from its seat when desired for unloading, and to enable the device to be so constructed that it may be conveniently applied to the plate valve.

The invention is illustrated in one of its preferred forms in the accompanying drawing, which is a longitudinal sectional elevation of a plate valve unloader embodying the 20 invention.

Referring to the drawings, a portion of the cylinder A of the compressor is shown having the head B. A plate valve, which includes the valve seat C, the stop plate D, the 25 valve plate E and the stud F, is inserted in the opening G in the wall H of the cylinder. A valve cover J is adapted to close the opening in the outer wall K of the compressor, opposite the plate valve and a suitable stud L carried by the cover J cooperates with the stud F of the plate valve and holds the valve seat C in the opening G.

In accordance with this invention, the 30 valve cover J is provided with a plurality of piston chambers O closed by perforated caps or plugs P to which pipe connections Q may be connected. Pistons R operate in the piston chambers O and are preferably hollow and provided with piston extension S extending outwardly beyond the portions of the 35 valve cover J forming the chambers. Springs T are preferably adapted to be compressed between the heads of the piston and the ends of the piston chambers, so that upon 40 relieving the fluid pressure, against the piston heads, the springs T will retract the pistons.

Each piston is provided with a plunger U and plunger springs V, located in the hollow 45 pistons R and held in position by the plugs

W tending to force the plungers outwardly. The plungers U are adapted to bear upon the valve plate E and hold it from its seat when the pistons R move outwardly in their piston chambers. A portion of an air receiver X 50 is shown connected by the pipe Y to a suitable pressure controlled pilot valve Z, and it is to be understood that a valve of the type shown in United States Patent No. 1,138,278, granted May 4, 1915, to J. H. Castle and 55 W. G. Rogers, may be used, which is so constructed that the valve operates to admit a certain predetermined receiver pressure to an unloading mechanism such as the plate valve unloader shown herein, until the receiver pressure falls a certain amount below that required to operate the pilot valve, in which case the pilot valve returns to its original position, allowing the pressure chambers of the plate valve unloader to exhaust to atmospheric pressure. I have merely indicated the valve chest 10, the adjustable valve plug 14, and the spring cup 28, corresponding to similar parts similarly numbered in the said patent, it being understood that any 60 other type of pilot valve may be used in the location indicated by the valve Z and this valve forms no part of my invention.

In the operation of the device, the pistons R and plungers U operate together, and the 65 plungers act directly on the inlet plate valve E. When the pressure in the receiver X becomes sufficient to operate the pilot valve Z, allowing fluid pressure to pass to the piston chambers O of the unloader, the resistance of 70 the piston springs T is overcome. The pressure from the receiver X forces the unloader pistons and unloader plungers outwardly until the plungers open the inlet valve. The compressor remains unloaded as long as 75 there is sufficient pressure in the receiver to operate the pilot valve Z. The plunger springs V acting on the plungers, hold the inlet valve E open during the return stroke of the compressor piston when unloaded. 80 The piston springs T hold the pistons and plungers away from the inlet valve when the compressor is building up pressure in the receiver.

I claim:

1. A plate valve unloader, comprising a plate valve and its seat, stop plate and stud, adapted to lie in a valve opening in the cylinder wall of a compressor, a valve cover over the valve seat having a plurality of 85

105

110

piston chambers, hollow pistons in said chambers, and plungers carried by the pistons and adapted to hold the said plate valve open.

- 5 2. A plate valve unloader, comprising a plate valve and its seat, stop late and stud, adapted to lie in a valve opening in the cylinder wall of a compressor, a valve cover over the valve seat having a plurality of piston chambers, hollow pistons in said chambers, retracting springs adapted to be compressed by the pistons, plungers carried by the pistons and adapted to hold the said plate valve open, and springs in said hollow pistons tending to hold said plungers outwardly.
- 10 3. A plate valve unloader, comprising a

plate valve and its seat, stop plate and stud, adapted to lie in a valve opening in the cylinder wall of a compressor, a valve cover over the valve seat having a stud for holding the plate valve structure to its seat in the wall of the compressor, a plurality of piston chambers in said valve cover, hollow pistons in said chambers, retracting springs 25 within the said chambers adapted to be compressed by the pistons, plungers carried by the pistons and adapted to hold the said plate valve open, and springs in said hollow pistons tending to hold said plungers outwardly.

In testimony whereof I have signed this specification.

FREDERICK W. PARSONS.
